UNITED STATES PATENT OFFICE.

WILLIAM HANSEN, OF CHICAGO, ILLINOIS.

WASHING MACHINE.

Application filed May 26, 1922. Serial No. 563,907.

To all whom it may concern:

Be it known that I, WILLIAM HANSEN, a citizen of the United States, residing at Chicago, in the county of Cook and State of Illinois, have invented certain new and useful Improvements in Washing Machines, of which the following is a specification.

The present invention relates to improvements in domestic washing machines, now in general use in households as well as laundries, wherein the clothes are introduced into an oscillating, revolving or similar movable receptacle and agitated for a suitable length of time to remove the soil.

The efficacy of processes of cleansing by these manually and mechanically operated devices very greatly depends upon the preliminary treatment of the clothes, unless the expedient of use of chemicals is resorted to which is not in any way desirable in view of the deleterious effect upon the fabrics. That is to say, it is quite customary to place the soiled clothes in soak over night or for a considerable period of time preliminary to washing them in order that the dirt may be softened and more easily be removed when the clothes are agitated in the washing operation of the apparatus. However, even with this preliminary treatment, it is practically necessary to resort to spot-rubbing,—that is, rubbing of the soiled spots by hand upon an ordinary washboard, or rubbing such spots between the hands after soaping in each instance. This is rather a tiring process and it has, therefore, been my object to facilitate the initial rubbing operation for this purpose by providing a mechanical rubbing element in conjunction with the washing apparatus, thereby further eliminating the drudgery attendant upon the washing of clothes as generally practiced.

To this end this invention comprehends the provision of a revolving or oscillating member operated from the power instrumentalities of the washing machine and having a surface corrugated, ribbed or similarly formed to enable the operator to hold those articles which need such preliminary treatment thereagainst for a short time to subject them to a rubbing action prior to introduction into the washing receptacle.

An important feature of my invention resides in the provision of an auxiliary com-

partment having communication with the water receptacle of a washer, whereby to permit the water in said receptacle to stand at the water level of the main receptacle and to thereby afford a common drainage arrangement, the rubbing member being disposed within this auxiliary receptacle and mechanically operated at will from the usual power source.

With these and other objects in view, the invention consists in certain combinations and arrangements of the parts as will more fully appear as the description proceeds, the novel features thereof being pointed out in the appended claims.

In the drawings:

Figure 1 is a fragmentary plan view of a washing apparatus having my invention applied thereto.

Figure 2 is a side elevation thereof.

Figure 3 is a transverse sectional view on the line 3—3 of Figure 2.

Figure 4 is a fragmentary plan view, showing a modified arrangement of my rubbing device.

Figure 5 is a sectional view on the line 5—5 of Figure 4.

Figure 6 is an enlarged plan view showing a modification of the rubbing surface of the rubbing cylinder.

Figure 7 is a fragmentary plan view showing a rubbing device of a modified type.

Figure 8 is a transverse sectional view on the line 8—8 of Figure 7.

Figure 9 is a plan view of a modified form of the rubbing member of the general type shown in Figures 7 and 8.

Corresponding and like parts are referred to in the following description and indicated in all of the views of the drawings by like reference characters.

Referring to the drawings, and particularly Figures 1 to 3, 1 indicates the water receptacle or tank of a conventional form of washing machine in which is journaled the rotating or oscillating clothes cylinder or drum 2. Upon the base of the machine is mounted the motor 3 having the drive shaft 4 thereof extending into the gear case 5. A shaft 6 extends from this gear case upwardly to the axis of the cylinder 2 to which it is operatively connected for the purpose of actuation of the cylinder in the process of washing.

At one side of the receptacle 1 is formed an extension or auxiliary compartment 7, having mounted at one side therein a rubbing cylinder 8 over which extends an apron 9 provided with an opening 10 exposing a portion of the surface of the rubbing member. The surface of said member is ribbed or corrugated, as clearly shown in the drawings, so as to provide a rubbing action in the use of the invention as later described. The partition wall between the compartment 7 and the main receptacle 1 is provided with one or more openings 11 through which the water from the main compartment may pass to the auxiliary compartment and seek the same level as in the former. It will be apparent that in the drainage of the water from the washing machine the usual drain, not shown, will carry off the water from both the main and the auxiliary compartments by virtue of this communication. Extending from the gear case 5 is a shaft 12 which is operatively connected with the shaft 13 on which the rubbing cylinder 8 is carried, said shaft being journaled in the ends of the auxiliary compartment 7. A clutch element 14 is provided whereby the shaft 13 may be actuated from the motor 3 at will as and when it may be desired to employ the rubbing device for the purposes intended.

In the use of the apparatus, the clothes which may have been previously soaked are spot-rubbed whenever found necessary by soaping the part which it is desired to cleanse and holding this portion of the fabric against the exposed surface of the cylinder 8 while the latter is rotated. The clothes as rubbed may be allowed to stand in the auxiliary compartment if the clothes cylinder in the main compartment is operating or may be directly thereafter placed in the clothes cylinder 2 if the latter is not being operated at that particular time. The apron 9 forms a support for the clothes which are being held in rubbing position and prevents the clothes from becoming entangled about the cylinder during the rubbing action.

Passing now to the form disclosed in Figures 4 and 5, it will be observed that this constitutes a similar arrangement excepting that the rubbing cylinder 8' is arranged at right angles to the position shown with respect to the form disclosed in Figure 1. With this arrangement a counter shaft 15 is employed to operatively connect the rubbing cylinder with the driving means extending from the drive shaft 4. By virtue of this arrangement of the cylinder the apron 9' is given a different configuration but serves the same purpose as described with reference to the preferred form.

In Figure 6 I have illustrated a cylinder in which the ribbing is arranged differently

from that disclosed in the figures hereinbefore referred to, the ribs having a diamond shaped arrangement at each end of the cylinder 8'' which arrangement would afford an excellent rubbing surface for an apparatus of this type.

Passing now to Figures 7 and 8, it will be noted that they depict a rubbing device of an entirely different type, being disk-like in form as indicated at 8^a, the apron 9^a being provided with a circular opening 10' exposing the flat surface of the rubbing member its full extent. This surface is either provided with a rib arrangement such as shown in Figure 7 or a similar rib arrangement as shown in Figure 9 and the member 8^a is rotated by means of the shaft 16 from the drive shaft in an obvious manner.

It will be understood that the ribbed surface of the rubbing device may be of metal, glass or wood and I do not wish to be limited as regards the material which may be employed for this purpose.

It will be further obvious that the provision of a rubbing instrumentality of this nature in conjunction with a washing machine embodies a very useful combination of elements for performing the ordinarily laborious operation of washing clothes.

It is within the purview of this invention, however, to employ the idea without regard to a direct attachment to or combination with a clothes washing machine, because a machine of the principles of my rubbing device would serve to accomplish the rubbing of clothes mechanically in performing the washing operation after the usual manner.

I desire it to be understood that the rubbing device may be applied to washers of different constructions from that disclosed herein and other changes in details of the arrangements may be made without departing from the spirit of the invention and within the scope of the claims hereto appended.

Having thus described my invention, what I claim as new and desire to secure by Letters Patent is:

1. A combined washing and rubbing machine comprising a water receptacle, a clothes receptacle therein, means for actuating the same, an auxiliary water compartment supported upon the water receptacle and communicating therewith to establish a common water level, a rubbing device in said compartment, and operating means for said device.

2. A clothes rubber comprising a receptacle, an exposed rubbing member mounted therein and having its surface formed with ribbed elements to impart rubbing action when the clothes are manually pressed against the same, an inclined guard apron

and support for the clothes adjacent said member, and means for actuating said rubbing member.

3. In a clothes rubber of the class described, a receptacle, a rubbing member mounted thereon, means for actuating said rubbing member, and a shield extending from the base of the receptacle to said rubbing member and forming a clothes compartment in which the clothes are protected from the rubbing member.

4. A combined washing and rubbing machine comprising a water receptacle, a clothes receptacle therein, means for actuating the same, an auxiliary water compartment extended from one side of the water

receptacle and communicating therewith at its base to establish a common water level in both the water receptacle and compartment, a rubbing device in said compartment, 20 and operating means for said device.

5. In a washing machine, a water receptacle, means for agitating clothes therein, an auxiliary water receiving compartment communicating with the first mentioned receptacle to provide a feed and drain connection to said compartment, a rubbing device mounted in said auxiliary compartment, and means for actuating said rubbing device.

In testimony whereof I affix my signature.

WILLIAM HANSEN.
